UNITED STATES PATENT OFFICE

106,455

DESIGN FOR A PLASTIC SHEET OR SIMILAR ARTICLE

Craig R. Sheaffer, Fort Madison, Iowa, assignor to W. A. Sheaffer Pen Company, Fort Madison, Iowa, a corporation of Delaware

Application June 25, 1937, Serial No. 70,054

Term of patent 7 years

To all whom it may concern:

Be it known that I, Craig R. Sheaffer, a citizen of the United States, residing at Fort Madison, in the county of Lee and State of Iowa, have invented a new, original, and ornamental Design for a Plastic Sheet or Similar Article, of which the following is a specification, reference being had to the accompanying drawing, forming a part thereof.

Figure 1 is a plan view of a flat plastic sheet or similar article, showing my new design; and

Fig. 2 is a front elevational view of the flat

plastic sheet of Figure 1, bent into the form of a tube and showing my new design.

The dominant feature of my design is the ornamentation appearing on the sheet and is independent of the thickness and configuration of the sheet.

I claim:

The ornamental design for a plastic sheet or similar article, substantially as shown and described.

CRAIG R. SHEAFFER.
